VERTICALLY ADJUSTABLE SCAFFOLD CONSTRUCTION

Glen W. Bohn, Mount Horeb, Wis.
Filed Aug. 24, 1955, Ser. No. 530,369
11 Claims. (Cl. 254—4)

This invention comprises a novel and useful vertically adjustable scaffold construction and more specifically relates to a scaffold having an adjustable platform whereby objects may be positioned at vertically adjustable heights to facilitate handling the same.

The principal object of this invention is to provide a scaffold having a vertically adjustable platform whereby light fixtures or other objects may be easily vertically adjusted and held in position to facilitate their application to a ceiling or other location.

A further object of the invention is to provide a scaffold construction in accordance with the foregoing object in which there shall be provided a simple, sturdy and highly serviceable means for vertically and adjustably positioning a platform at various desired elevations.

Yet another object of the invention is to provide a scaffold construction having improved brace means whereby the scaffold may be rigidly braced in position against sway or tilting, and this despite any irregularities in the surface upon which the scaffold is mounted; and whereby the brace means may be easily and adjustably lowered into an operative position or lifted into an inoperative position by an actuating means from an upper portion of the scaffold.

A still further important object of the invention is to provide an improved scaffold construction wherein a pair of leg assemblies are connected together in a rigid improved manner and by a member which also supports the flexible elevating means.

A still further object of the invention is to provide a scaffold construction in accordance with the above mentioned objects in which a novel support construction is provided facilitating a workman's use of the scaffold and also serving to assist in rigidly uniting and bracing the two leg assemblies of the same.

These together with other objects and advantages which will become subsequently apparent reside in the details of construction and operation as more fully hereinafter described and claimed, reference being had to the accompanying drawings forming a part thereof, wherein like numerals refer to like parts throughout, and in which:

FIGURE 1 is a top plan view of a preferred embodiment of a scaffold in accordance with the principles of this invention;

FIGURE 2 is an end elevational view taken from the left end of FIGURE 1, a part of the scaffold elevating means being broken away;

FIGURE 3 is a side elevational view taken from the right end of FIGURE 2, parts being broken away and shown in vertical section and showing the platform in its lowered position;

FIGURE 4 is a detail view taken upon an enlarged scale in vertical transverse section substantially upon the plane indicated by the section line 4—4 of FIGURE 3 and showing certain details of the platform elevating mechanism;

FIGURE 5 is a horizontal sectional view taken substantially upon the plane indicated by the section line 5—5 of FIGURE 3;

FIGURE 6 is a detail view taken substantially upon the plane indicated by the section line 6—6 of FIGURE 1 showing the manner in which another longitudinal beam is detachably secured to one of the leg assemblies for rigidly uniting the latter; and

FIGURE 7 is a further detail view taken substantially

2

upon the plane indicated by the section line 7—7 of FIGURE 2 and showing the manner in which the foot board is adapted to embrace a rung of an end assembly and assist in rigidly uniting the two end assemblies of the base.

5 In the accompanying drawings, which illustrate merely by way of exemplification of the principles of the invention, one suitable embodiment of the apparatus in accordance with the same, it will be seen that there is provided a base indicated generally by the numeral 10 and upon 10 which is mounted for adjustable vertical elevation, a platform indicated generally by the numeral 12. As shown more clearly in FIGURES 2 and 3, the base 10 consists of a pair of end assemblies, each of which is a form of ladder. Thus, each end assembly includes a pair of side 15 rails 14 between which are rigidly connected a plurality of vertically spaced rungs 16. The side rails are preferably of a tubular construction and the rungs, as shown in the detail view of FIGURE 7, may be of square cross-section and may be either hollow or solid, as desired. In 20 their lower ends the side rails 14 of the end assemblies are provided with casters 18 whereby the entire scaffold is rendered easily mobile to position the same at any desired location.

At the upper end of the leg assemblies of the scaffold, 25 there is provided a horizontally extending beam 20 which is preferably an angle iron member, as shown in the detail views of FIGURES 4 and 6, and as will be also apparent from FIGURE 2. At its opposite ends, the beam 20 is provided with a pair of depending cylindrical 30 projections or pins 22, see FIGURE 6, which are adapted to be seated in sockets formed by the upper ends of the tubular side rails 14. The beam 20 thus provides a connecting member or connecting means for rigidly uniting the two end assemblies into a unified base. To assist in 35 rigidly connecting the end assemblies together, there are also provided suitable diagonally disposed bracing or tie rods 24, as shown in FIGURE 3. These connect the upper portion of one leg assembly with the lower portion of the other leg assembly at what may be termed the 40 back or closed side of the base, this being the side beneath the horizontal beam 20.

There is also provided a foot board 30 which serves the dual functions of rigidifying the connection of the two leg assemblies into the base and also provides a walk for 45 workmen when handling the articles carried by the platform and when the latter is in a raised position. The foot board, as shown in FIGURE 7, is provided adjacent each of its ends and on the underside of the same with sets of angle iron members 32 and 34. These angle iron 50 members may be bolted to the board and welded to each other and have their vertical depending flanges spaced from each other a distance to snugly receive a rung 16 therebetween. Consequently, when the foot board is placed in vertically adjusted position upon the leg assemblies, as by placing the same upon a predetermined pair of rungs, the sets of angle iron members at each end of the foot board will embrace the corresponding rung and thus rigidly lock the two leg assemblies together.

Referring next primarily to FIGURES 2—4, it will be 60 seen that the means for supporting and vertically adjusting the platform assembly 12 consists of a pair of vertically slidable telescoping outer and inner members 40 and 42, respectively. The member 40 at its upper end is rigidly secured to the vertical depending flange of the 65 horizontal beam 20 at substantially the midportion of the same, as by welding or the like, this being indicated at 44 in FIGURE 5. It will be understood that any other suitable means may be provided for fastening the member 40 thereto. Adjacent its lower end, a brace means in the 70 form of a strap constituting a bracket 46, see FIGURE 4, is provided, the same being secured as by a wing nut and bolt 48 to a lower portion of the outer telescoping

member 40 and encircling the brace rods 24 previously mentioned. It will also be observed that the member 40 is in the form of a hollow rod or sleeve, being open at its upper and lower ends, and having its lower end cut upon a bevel, as indicated in dotted lines at 50 in FIGURE 4, and also as shown in FIGURE 2. The inner telescoping member 42, which may be either hollow or solid, is slidably received within the outer member 40 and extends beyond both ends of the same. Preferably, however, at its lower end, the member 42 is provided with an opening or socket 52 in which is received the upper end of an L-shaped member 54. The latter is rigidly secured in the socket in any suitable manner. The horizontally projecting portion of the member 54 constitutes a guide member which is adapted to be received in a guide slot 56, see FIGURE 3, which opens from the lower end of the outer member 40 and extends a considerable length upwardly in the same. The lower end of the guide slot is positioned at the highest portion of the beveled surface 50 previously mentioned.

As the inner member 42 is raised, the member 54 projecting therefrom will be guided by the inclined edge 50 to enter the lower end of the guide slot, and upon further upward movement of the inner section of the telescoping assembly, will travel upwardly in guided relation to the longitudinal slot 56.

Means are provided for lifting the inner member and the platform carried thereby to vertically adjusted positions. For this purpose, as will be best apparent from FIGURES 3, 4 and 5, there is provided a mounting bracket 60 welded or otherwise secured to the outer member 40 adjacent the upper end of the latter and a crankshaft 62 is mounted in this bracket to constitute a winch or windlass, a cable 64 being attached thereto. The other end of this cable, as shown best in FIGURE 4, is secured to an eye 66 at the outer end of the horizontally projecting arm of the member 54. It will thus be apparent that by manipulating the winch, vertical sliding movement may be imparted to the inner member 42, and the latter will be guided during its upward and downward travel in the outer member 40 by engagement with the horizontally projecting arm of the member 54 in the guide slot 56 previously mentioned.

In order to lock the telescoping members, and the platform carried thereby, in vertically adjusted position, there is provided, as shown best in FIGURE 4, a locking ratchet in the form of a ratchet wheel 68 attached to one end of the crankshaft 62, and which cooperates with a pivoted ratchet or pawl 70 which is pivoted to the bracket 60 and is yieldingly urged, as by a spring 72, into engagement with the ratchet wheel. Thus, once the telescoping sections have been adjusted by means of the winch, the spring urged ratchet assembly will maintain them in adjusted position.

At its upper end, the inner telescoping member 42 is provided with a diametrically reduced portion or extremity 80. Preferably, this extremity is externally screw threaded, as at 82, for reception in an internally threaded nipple or socket 84 which is secured to the underside of a platform 86 forming a part of the platform assembly 12. In order to reinforce and strengthen the latter, the underside of the platform is provided with a pair of longitudinally extending, laterally spaced angle iron members 88 between which the nipple 84 is placed and to which it may be secured, as by welding or the like.

When it is desired to increase the vertical position of the platform with respect to the telescoping lifting members, extending elements may be interposed between the nipple 84 and the extremity 80, as desired.

Reference is next made to FIGURES 2 and 3 for a description of an adjustable brace means which may be employed in order to more rigidly and securely position the scaffold upon uneven flooring and the like. For this purpose, there is attached to one of the leg assemblies a pair of braces. Each brace consists of a curved leg 90 having a foot member 92 at its lower end adapted to

engage upon the floor or other surface, and at its upper end being pivoted, as at 94, to a collar 96 which rotatably encircles one of the uprights 14 of a leg assembly between a pair of the rungs thereof. The leg 90 is thus pivoted to the end assembly for vertically pivoting movement with respect thereto.

At the lower portion of that upright of the leg assembly, there is provided a second sleeve or collar 97 to which is pivoted a lever 98 at one extremity as by a pivot pin or pins 100. The other end of this lever is pivoted, as at 102 to one end of a connecting link 104 whose other end is pivoted, as at 106, to the leg 90. A crank arm 108 is secured to the lever 98 in rigid relation so that upon actuation of the crank arm, the lever 98 will be pivoted between the positions of FIGURES 2 and 3, and through the associated connecting link will thus pivotally raise or lower the leg 90. In FIGURE 2, the leg is shown in its lowered or bracing position, while in FIGURE 3, it is shown in its raised position.

Referring now to FIGURE 3, it will be seen that a tension spring 110 is connected to the collar 97 and to the lever arm or crank 108 for yieldingly urging the latter into its lowered position, and thus through the link 104 pivot the leg 90 into its raised or inoperative position. A flexible cable or the like 112 is attached to the outer end of the arm 108 and is provided with a hook 114 which is positioned at the upper portion of the base. By means of this hook, the lever arm or crank may be raised, thereby causing the lever 98 and link 104 to pivot the leg 90 into its lowered position. The spring 110 will tend to raise the leg 90, as shown in FIGURE 3.

It will thus be seen that the brace means can be raised or lowered by remote control by the worker from the upper portion of the base of the scaffold.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. An adjustable portable scaffold comprising, a base consisting of a pair of detachable leg assemblies having supporting casters and detachable connecting means rigidly uniting the upper ends of said leg assemblies, a platform and lifting means operatively secured to said base, connecting means and platform for adjustably elevating the latter.

2. An adjustable scaffold comprising, a base consisting of a pair of leg assemblies and connecting means rigidly uniting said leg assemblies, a platform, lifting means operatively secured to said base and platform for adjustably elevating the latter, said leg assemblies each including a socket at their upper ends, said connecting means including a beam having a flange engaging a side of the leg assemblies and projections on said beam detachably seated in said sockets.

3. The combination of claim 1 wherein said leg assemblies each include a socket at their upper ends, said connecting means including a beam having a flange engaging a side of each leg assembly and projections on said beam seated in said sockets, said lifting means being carried by said beam.

4. The combination of claim 1 wherein said lifting means includes relatively slidably vertically telescoping elements, means fixedly securing said platform to one of said elements, means mounting the other element to said base, operating means carried by one of said elements and operatively connected to both of said elements for causing adjusted vertical movement thereof, one of said elements having a vertical guide slot and the other element having a member slidably engaged in said guide slot.

5. The combination of claim 1 wherein said lifting means includes relatively slidably vertically telescoping elements, means fixedly securing said platform to one of said elements, means mounting the other element to said base, operating means carried by one of said elements and operatively connected to both of said elements for causing adjusted vertical movement thereof, one of said elements having a vertical guide slot, the other element having a member slidably engaged in said guide slot and said operating means being attached to said member.

6. The combination of claim 1 wherein said lifting means includes relatively slidably vertically telescoping elements, means fixedly securing said platform to one of said elements, means mounting the other element to said base, operating means carried by one of said elements and operatively connected to both of said elements for causing adjusted vertical movement thereof, one of said elements having a vertical guide slot, the other element having a member slidably engaged in said guide slot and inclined guide surfaces convergent upon the open end of said guide slot.

7. The combination of claim 1 including a brace comprising a leg having a foot at its lower end for engagement with a surface upon which said base rests, means pivotally mounting the upper end of the leg to the leg assembly for vertical pivoting movement between a raised position and a lowered surface engaging position and means for actuating said leg.

8. The combination of claim 1 including a brace comprising a leg having a foot at its lower end for engagement with a surface upon which said base rests, means pivotally mounting the upper end of the leg to the leg assembly for vertical pivoting movement between a raised position and a lowered surface engaging position, means for actuating said leg, said actuating means including a link connected to said leg and an actuator for operating said link.

9. The combination of claim 1 including a brace comprising a leg having a foot at its lower end for engagement with a surface upon which said base rests, means pivotally mounting the upper end of the leg to the leg assembly for vertical pivoting movement between a raised position and a lowered surface engaging position, means for actuating said leg, said actuating means including a link

connected to said leg, an actuator for operating said link and said actuator including a member operable from the upper end of said base.

10. The combination of claim 1 including a brace comprising a leg having a foot at its lower end for engagement with a surface upon which said base rests, means pivotally mounting the upper end of the leg to the leg assembly for vertical pivoting movement between a raised position and a lowered surface engaging position, means for actuating said leg, said actuating means including a link connected to said leg, an actuator for operating said link, said actuator including a member operable from the upper end of said base, a lever pivotally mounted on said base and said link and said member being attached to said lever.
11. The combination of claim 1 including a brace comprising a leg having a foot at its lower end for engagement with a surface upon which said base rests, means pivotally mounting the upper end of the leg to the leg assembly for vertical pivoting movement between a raised position and a lowered surface engaging position, means for actuating said leg, a pair of collars mounted upon said leg assembly for rotating said leg and said actuating means being secured to said collars, whereby said brace may be folded flat against the leg assembly.
